[57] CLAIM

The ornamental design for a nozzle for hand operated trigger sprayer, substantially as shown and described.

DESCRIPTION

FIG. 1 is a perspective view taken from the top, front and right side of a nozzle for hand operated trigger sprayers, showing my new design;

FIG. 2 is a right side elevational view thereof, the left side being a mirror image of the right side shown;

FIG. 3 is a top plan view thereof;

FIG. 4 is a bottom plan view thereof;

FIG. 5 is a front elevational view thereof; and,

FIG. 6 is a rear elevational view thereof.

FIG. 1

FIG. 2

FIG. 3

FIG. 4

FIG. 5

FIG. 6
